DRAFTING INSTRUMENT

Oscar F. Graff, Washington, D. C.

Application April 2, 1946, Serial No. 659,045

3 Claims. (Cl. 33—93)

1

This invention relates to a drafting instrument and may be more specifically defined as a combined square, protractor, triangle, scale and straight edge.

The invention relates to a drafting instrument which combines several of the basic instruments used by draftsmen into a readily available, simple, compact and light article of manufacture.

The invention is so constructed and arranged that it is adapted for use directly on a drawing tablet or a drawing board in which the edges of the tablet or board serve as a guide to assist in properly positioning the drafting instrument relative thereto.

One of the objects of the present invention is to provide a device as described in which the triangle may be adjusted relative to suitable guide members so that the triangle may be positioned at any desirable angle with reference to the guide in order that the many forms of drafting may be performed.

A further object of the invention is to provide means for latching the triangle in any of a number of adjusted positions relative to said guide members and in which the latching operation entails the simple operation of grasping the guide members which releases the latch and at the same time permits relative movement between the guide members and the triangle.

An additional object is the provision of a sight opening in one of the guide members which enables the draftsman to visually ascertain the correct setting of the triangle with reference to the guide members and the guide members are so attached to the triangle that one edge thereof may be placed directly against the drawing board or tablet so as to serve as a straight edge throughout the length thereof. To this end the guide members are terminated at a point spaced from the straight edge and the guide members are reduced in thickness so that by a simple tilting operation the straight edge may be placed directly against the drawing surface without any interference from the guide members which are relatively thick as compared to the thickness of the triangle.

A further object is to provide an instrument of the character described in which the triangle and guide members may be quickly and accurately set to a 45° angle or returned to the original working position at 90°.

An additional object is the provision of a drafting instrument such as disclosed in which the guide members are provided with indented gripping surfaces to facilitate grasping of the same

2

by the draftsman and the guide members, which are preferably formed of moulded material, are hollowed out wherever possible to eliminate weight without sacrificing strength.

5 In devices heretofore known of the present type, it has been found that the relative movement between the triangle and guide members causes scratching and mutilation of the surface of the triangle due to the fact that there are large areas of contact between the triangle and guide members. However, in my device the guide members are spaced from the triangle throughout a large portion of their length so that a minimum contact between the triangles and guide members is provided, thereby eliminating to a large extent the scratching, rubbing or mutilation heretofore known.

Other objects and advantages will be apparent as the description proceeds, it being understood that the illustrated embodiment depicts the preferred form of the device but that changes in proportions, finish and the like may be resorted to so long as they fall within the spirit of the invention as defined in the appended claims.

20 Reference is made to the drawings attached hereto and forming part hereof wherein like reference numerals refer to corresponding parts throughout the figures and in which:

Figure 1 is a perspective view of my invention.

Figure 2 is a fragmentary plan view showing the guide members and triangle in their normal position of use.

Figure 3 is a broken sectional view taken along the line 3—3 of Figure 2.

35 Figures 4 and 5 are transverse sectional views taken along the lines 4—4 and 5—5 respectively of Figure 2.

Figures 6 and 7 are transverse sectional views taken along the sectional lines 6—6 and 7—7 respectively of Figure 3.

40 Figures 8, 9 and 10 are diagrammatic illustrations of the various manners in which the triangle is used in connection with a drawing board or the like.

45 Figure 11 is a fragmentary sectional view of a modified construction of the latch.

Referring now in particular to the drawing, the present invention deals with a drafting instrument composed of a transparent triangle, 10, and a guide member 11 composed of an upper guide member 12 and a lower guide member 13 pivotally attached to the triangle by the rivet 14 passing through the reduced ends 15 and 16 of the guide members and through the triangle so that the triangle is free to swing about the rivet

14 and between the guide members 12 and 13 so that the triangle may be positioned at various angles relative to the inner straight guiding faces of the guide members 12 and 13.

As here illustrated, the guide members 12 and 13 are formed of moulded material such as rubber, synthetic resin or the like, and in order to reduce the weight thereof they are hollowed out as at 17 and 18.

It should be noted that the guide members 12 and 13, which are reduced at the ends 15 and 16, have the ends of these reduced portions spaced inwardly from the straight edge 19 of the triangle so that the guide members and triangle, as a unit, may be removed from the usual working position whereby a guide member is in contact with the side edge of the drawing board, and placed directly over the drawing, then tilted to bring the straight edge 19 flatly into contact with the drawing surface throughout its length when occasion demands, whereas, if the guide members 12 and 13 were extended to the edge 19, such edge would be spaced from the drawing surface and could not be brought directly into contact therewith at this point. This would result in flexing the triangle where it is desired to lay the edge 19 flatly on the drawing surface.

The guide members 12 and 13 are provided with aligned spacing lugs 20 and 21, respectively, which project beyond the planes of the opposed faces of the guide members and contact the face of the triangle 10.

The reduced end portions 15 and 16 likewise are held in engagement with the face of the triangle by means of the rivet 14 but at all other portions the triangle is free from contact with the guide members so that rubbing or scratching of the triangle in its movement relative to the guide members is limited to a restricted area and the adjustment is thereby rendered less difficult.

The triangle 10 is provided with an arcuate slot 22 which receives the stud 23, here shown as integrally formed with the lower guide member 13, but of course this stud could be positioned on either guide member without affecting the results.

The stud 23 projects into the arcuate slot 22 and limits the movement of the triangle relative to the guide member. By means of this slot the triangle may quickly be set to a 45° angle and returned to its original 90° angle position.

As shown clearly in Fig. 1, the triangle is provided along two of its edges with suitable scales 24 and 25, it being noted that the scales read from right to left as indicated in Fig. 1.

The triangle is also provided with an arcuate scale 26 and below the scale 26 there is provided a series of arcuately arranged apertures 27.

The upper guide member 12 is provided with a sight opening 28 extending therethrough and presenting an inclined face 29 upon which is placed an index line to facilitate visual determination of the proper adjustment of the triangle relative to the guide members.

The width of the scale 26 is substantially the width of the sight opening 28 and the scale 26 in its arcuate arrangement passes beneath the sight opening 28 as the triangle is moved. Therefore the individual markings of the scale may be arcuately aligned with the index line on the inclined face 29 so that proper positioning of the triangle may be readily ascertained. Obviously, the lower guide member may likewise be provided with a sight opening similar to that just described.

The upper guide member 12 is also provided with a recess 30 which opens outwardly of the end 31.

The end 31 and the corresponding end of the lower guide member 13 are secured together by a rivet 32 passing through the said ends and also through an elongated opening 33 in a latch 34 pivoted to the upper member as at 35.

The latch 34 is provided with a tapered stud 36 and is normally biased toward the triangle 10 by means of a spring 37 so that upon registry with one of the openings 27 the stud will be projected into the same and latch the triangle 10 to its adjusted position.

By reference to Fig. 3 it will be seen that the lower guide member 13 is provided with a countersink 38 into which the triangle 10 fits so that the triangle lies flush with the upper surface of the guide member 13, although not actually touching the guide member due to the spacing lug 21. The stud 36 of the latch projects below the under face of the upper guide member 12 and rides over the upper face of the triangle until it registers with an aperture 27 whereupon it is projected into the same by the spring 37.

The upper guide member 12 has its end 31 terminating short of the end 39 of the lower guide member 13 and the finger piece of the latch 34 which projects beyond the end 31 of the upper member is positioned above the reduced end 39 so that the finger piece of the latch 34 and the reduced end 39 form gripping surfaces by means of which the operator may readily grasp the same for the purpose of depressing the outer end of the latch 34 to thereby release the stud 36 from its aperture after which the guide members and triangle may be swung relative to each other without the necessity of releasing the grip on the latch 34 and end 39. After the correct position between the guide members and triangle has been assumed, release of the latch 34 will cause it to hold the triangle and guide members in adjusted position.

It is readily apparent that it is not essential that the triangle be provided with a series of apertures as at 27, and in Fig. 11 I have shown another form of latching mechanism for accomplishing the same purpose. In this form the tapered stud 36 is replaced by an elongated tapered projection 40 carried on the undersurface of the latch and the triangle is provided with a series of arcuately arranged elongated grooves 41 to receive the projection 40.

An examination of Figs. 1, 4 and 5 clearly shows that the upper and lower guide members are recessed as at 42 and 43 on the side faces thereof which provide a ready hand hold by means of which the instrument may be picked up or manipulated.

It has been found in the use of triangles of the type here disclosed where the center portion is open that when the triangle is used on a drafting board in which the drafting material is held in position by means of thumb tacks or the like, that it very often happens that the triangle must be positioned on the board so that one or more of the thumb tacks lie within the open space within the borders of the triangle.

In such position when an attempt is made to slide the triangle along the board, the edges of the triangle surrounding the interior opening engage the tacks or the like and the triangle must be elevated from the board in order that it may slide over the heads of the tacks.

In order to overcome the necessity for elevat-

ing the triangle, I provide the edges of the triangle bordering the interior opening with oppositely beveled surfaces as indicated at 44, so that in movement of the triangle along the board the beveled surfaces will ride over the heads of the tacks and eliminate the necessity for elevating the triangle.

While I have described the latch member as being carried by the upper guide member 12, it will be readily apparent that the latch could equally well be carried by the lower member and engage openings in the triangle from beneath or elongated grooves on the bottom face of the triangle.

From the foregoing it is clear that by providing the upper and lower guide members 12 and 13 the inner edges thereof act as guide faces for engagement with an edge of a drawing tablet or board and since the triangle is intermediate the upper and lower guide members, the triangle may be used in its normal position as disclosed in Fig. 1 or may be reversed or used upside down with equal facility, in which event the inner edge of the upper guide member 12 will engage the edge of the drawing board or tablet.

In view of this possibility it is clear that depending upon the position of the drafting instrument isometric or oblique drawings may be made and that with the scales arranged on the triangle as shown and the triangle being transparent, it is clear that when the same is used in its reversed or upside down position the scale on the long leg or hypotenuse may be read correctly.

From the foregoing it is also apparent that the present invention embodies a neat, compact and light weight instrument which is adaptable for a variety of forms of drafting. It may be used either in its reversed or normal position. Provision is made for accurately aligning the protractor scale within the sight window and the latch member is substantially completely hidden from view and does not project above the guide members so as to offer an obstacle to the draftsman when using the instrument. Furthermore, it is obvious that the invention is composed of a relatively small number of parts which may be cheaply manufactured, but yet which is of sturdy construction.

The arrangement of the latch 34 projecting beyond the end 31 of the upper guide member cooperating with the reduced grip 39 facilitates disengagement of the latch from the triangle and movement of the guide members relative to the triangle so that the single operation of manipulating the end of the guide members carrying the latch enables the draftsman to quickly and accurately position the triangle where desired.

I claim:

1. In a drafting instrument, an upper guide member and a lower guide member, a triangle pivoted thereto intermediate said guide members

for relative motion between the same, one of said guide members having a recess opening through one end thereof and a latch confined within said recess and having a finger piece extending therefrom beyond the free end of said guide member to overlie the lower guide member for operating said latch.

2. In a drafting instrument, an upper guide member and a lower guide member, a triangle pivoted to said guide members and lying between the same for movement between the guide members, a row of recesses on said triangle and a latch on one of said guide members engaging said recesses to lock the triangle in any one of a plurality of adjusted positions, one of said guide members extending beyond its opposed guide member to form a gripping portion, said opposed guide member carrying said latch, said latch having a finger piece extending from the end thereof and overlying the gripping portion on the other guide member.

3. In a drafting instrument, an upper guide member and a lower guide member having straight side edges, a triangle pivoted thereto intermediate said guide members for relative swinging movement therebetween, said triangle being provided with an arcuate row of openings so located as to pass between the guide members as the triangle is swung, one of said guide members having a recess therein opening through the end thereof and extending to a point beyond the row of openings and facing the opposed guide member, and a latch pivotally mounted on said recess and having one end extending beyond the open end thereof so as to be grasped to release the latch, the opposite end of the latch carrying a stud for engagement with any of the openings to lock the triangle in desired position, said latch member overlying the opposed guide member and terminating flush with the end thereof so that the latch may be released by squeezing the free ends of the opposed guide members.

OSCAR F. GRAFF.
